DISPLAY DEVICE

Bernard J. Stephens, Milwaukee, and Norman O. Lewis, Wauwatosa, Wis., assignors to Hiram Walker & Sons Inc., Peoria, Ill.

Application September 25, 1948; Serial No. 51,184

4 Claims. (Cl. 248—226)

1
This invention relates to an improved type of display device for packaged goods which is especially adapted for easy attachment to, and detachment from, a shelf or similar supporting ledge at any desired point thereon.

An object of the invention is to provide a display device of the character mentioned comprising a frame having a top wall with an opening therein for receiving an article to be displayed, a tray pivotally mounted on the frame below the top wall in position to support an article placed within the opening in the top wall, the top wall of the frame having an extension for engaging over a shelf panel and the tray having an extension disposed beneath the extension of the top wall for engaging against the under-face of the shelf panel, and a spring for pivoting the tray in the direction which will press the tray extension toward the extension of the top wall, said extension thus serving under the action of the spring as a clamp to removably secure the device to the shelf panel.

Other objects and advantages of the invention will appear from the following detailed description and drawings which illustrate a preferred embodiment of the invention.

Referring to the drawings:

Fig. 1 is a perspective view of the display device as applied to a shelf panel;

Fig. 2 is a top plan view of the device, a portion of the top wall of the frame being broken away to show the spring mechanism;

Fig. 3 is a partial section taken on line 3—3 of Fig. 2; and

Fig. 4 is an elevational view taken in the direction indicated by line 4—4 of Fig. 3.

In the embodiment shown, the device comprises a box-shaped frame consisting of a top wall 5, and side walls 6, 7, 8 and 9 depending therefrom; a tray or platform 11, pivotally supported within the frame below top wall 5 on a rod 12 which extends transversally of the frame between walls 6 and 8, the pivotal connection with tray 11 being provided by a pair of lugs 13 carried by the opposite sides of the tray and each provided with a hole for receiving rod 12; and a pair of coil springs 14 carried at the opposite ends of rod 12 between lugs 13 and the adjacent walls of the frame.

The frame and tray are preferably made of heavy sheet metal, as for example, sheet aluminum. The top wall 5 in the embodiment shown is provided with a circular opening 15 for receiving an article to be displayed, as for example a bottle 16 as shown in Fig. 3. This top wall 5 is provided with a jaw or extension for en-

gaging over a shelf ledge or panel 17, the extension in the embodiment shown being formed as an integral part of said top wall and consisting of two strips or prongs 18 positioned on either side of side wall 9.

2
The tray 11, which conforms generally to the shape of the frame in which it is supported, consists of a wall 19 and three side walls 21, 22 and 23 which extend downwardly from wall 19. The fourth side of wall 19 is bent upwardly at a slight angle, just below rod 12. This upwardly bent portion 24 is best shown in Fig. 3 and is the portion of the bottom wall to which the lugs 13 are secured. This inclined portion 24 of the bottom wall of the tray has formed as an integral part thereof two jaws or extensions 25 disposed beneath the extensions 18 of the top wall. These extensions 25 are designed to engage against the under face of shelf panel 17. The extremities of these extensions 25 are preferably bent slightly downwardly, as shown at 26, the downwardly inclined extremities serving as a guide to facilitate shoving the device on to shelf panel 17.

The tray 11 is pivoted by the coil springs 14 in a clockwise direction, viewing Fig. 3, one end 27 of each of said springs bearing upwardly against the under face of top wall 5 of the frame and the other end 28 of each of said springs bearing downwardly on the tray; said ends 28 being bent inwardly to extend through slots 29 formed in side walls 21 and 23, as shown in Fig. 4.

It will be apparent that under the action of coil springs 14 which tend to pivot tray 11 away from the top wall of the frame the tray extensions 25 are pressed upwardly against the under face of shelf panel 17. Thus, under this spring action, said extensions 25 co-act with extensions 18 to securely clamp the device onto shelf panel 17. The strength of springs 14 is such that this clamping action is sufficiently strong to hold the device in clamped position on the shelf under the weight of the article which the device is designed to display. It will be noted that the construction is such that the device may be readily mounted on, and removed from, the shelf panel 17. To mount the device it is merely necessary to shove it against the edge of the shelf until the frame wall 9 has come into contact with the shelf edge. As the device is thus shoved against the shelf panel, tray extensions 25 are moved downwardly against the tension of springs 14, the tray 11 being pivoted in a counter-clockwise direction, viewing Fig. 3, into a horizontal position, in which position it provides a flat support for the bottle 16. It will be further noted that the design is

such that the weight of bottle 16 tends to pivot tray 11 in a clockwise direction, viewing Fig. 3, thus augmenting the action of springs 14 and providing additional clamping force for securely holding the device on the shelf. The device is removed from the shelf by merely pulling it outwardly until extensions 18 and 25 are disengaged from panel 17.

The device is particularly well adapted for use in the display of bottled merchandise, although it can be so shaped as to readily lend itself to the display of other shaped package goods. In effect it serves as a shelf extender projecting as it does from the edge of the shelf to which it may be easily applied at any desired point.

It will be understood that the foregoing description of the preferred embodiment of the invention has been given for clearness of understanding only, and that the invention is not to be construed as limited to the details of this specific embodiment.

What we regard as new and desire to secure by Letters Patent is:

1. A display device comprising a frame, including a top wall with an opening therein for receiving an article to be displayed and an extension for engaging over a shelf panel, a tray pivotally mounted within the frame in position to support an article placed in said opening, said tray having an extension positioned beneath said top wall extension for engaging against the under face of a shelf panel, and spring means arranged to pivot the tray in a direction to press said tray extension toward the extension of the top wall, said extensions thus serving under the action of said spring means as a clamp to removably secure the device in display position on a shelf panel.

2. A display device comprising a frame having a top wall and side walls depending therefrom, said top wall having an opening therein for receiving an article to be displayed, a tray, means for pivotally supporting said tray between the side walls of the frame and in position to support an article placed in said opening, the top wall of said frame having an extension for engaging over a shelf panel and said tray having an extension positioned beneath said top wall extension for engaging against the under face of a shelf panel, and spring means carried by said pivotal support

50

means for pivoting the tray in a direction to press said tray extension toward the extension of the top wall, said extensions thus serving under the action of said spring means as a clamp to removably secure the device in display position on a shelf panel.

3. A display device comprising a pair of hinged members having opposed jaws arranged to engage a shelf ledge, one of said members having an opening for receiving an article to be displayed, the other being shaped to support such an article when placed in said opening, and spring means disposed between said hinged members for pivoting said jaws about the point of hinged connection into clamping position when in engagement with a shelf ledge.

4. A display device comprising a frame having a top wall, and a side wall depending therefrom for engaging against the edge of a shelf ledge, said top wall having an opening therein for supporting an article to be displayed, a tray, means for pivotally supporting said tray on the frame and in position to support an article placed in said opening, the top wall of said frame having a jaw projecting beyond the side wall for engaging over a shelf ledge and said tray having a jaw positioned beneath said first mentioned jaw for engaging against the under face of a shelf ledge, and spring means arranged to pivot the tray in a direction to press said jaws together, said side wall of the frame serving as a stop for engaging against the edge of a shelf ledge when the device is mounted thereon and said jaws serving under the action of said spring means as a clamp to removably secure the device to the ledge.
